UNITED STATES PATENT OFFICE.

JOHN E. BELL, OF BROOKLYN, NEW YORK, ASSIGNOR TO COMBUSTION ENGINEERING COMPANY, A CORPORATION OF NEW YORK.

PULVERIZED-FUEL-BURNING FURNACE.

Application filed November 11, 1920. Serial No. 423,235.

This invention relates to furnaces for burning pulverized fuel, particularly such as are used in the generation of steam.

One of the primary objects of my invention resides in the provision of an improved arrangement of furnace by means of which it is not only possible to obviate the slagging difficulties which are ordinarily incident to the burning of pulverized fuel but also to greatly increase the evaporative efficiency.

One of the more specific objects of my invention is to provide an improved form of water screen for pulverized fuel burning furnaces.

The foregoing, together with such other objects as may hereinafter appear, I obtain by means of a construction, the preferred embodiments of which are illustrated in the accompanying drawings, wherein:

Fig. 1 is a longitudinal section through a portion of a furnace embodying my improvements, taken on the line 1—1 of Fig. 2; Fig. 2 is a front elevation of Fig. 1; Fig. 3 is a sectional view corresponding to Fig. 1 but illustrating my invention with a modified form of boiler connection; Fig. 4 is a section on the line 4—4 of Fig. 3; Fig. 5 is a fragmentary section illustrating still another modification of boiler connection; Fig. 6 is a section through a boiler illustrating another embodiment of the invention; and Fig. 7 is a section on the line 7—7 of Fig. 6.

Referring now to Figs. 1 and 2, the combustion chamber A of the steam generating furnace, indicated as a whole by the reference letter B, is provided with an inlet burner C, preferably located in the top thereof, the number of said burners being varied as required. The burner (or burners) C is or are also located adjacent the front wall 1 of the combustion chamber so that the entering fuel or mixture of fuel and air will be subject to the radiant heat of such wall. The combustion chamber is provided at the top with an outlet 2 for the hot gases and other products of combustion which are drawn off under the influence of the draft, and above such outlet I arrange any suitable boiler setting such as the tubes 3 and headers 3^a. The mixture of fuel and air, or just the fuel itself, is admitted through pipe 4 and the flow thereof is aided, if desired, by means of a steam jet 5 or the like, in which connection I prefer that the

jet shall not be of high velocity. Supplemental air inlets 6 and 7 are provided for the burner and these, if desired, may be controlled by dampers 8.

Located in the wall 1 of the combustion chamber I provide a plurality of supplemental air inlets 9 for supplying such auxiliary air as may be necessary to complete combustion, such inlets being controlled by dampers 10 which, if desired, may be operated in unison, as by means of a chain 11.

The water screen for the combustion chamber is composed of tubes 13^a and tubes 13^b, such tubes being located some distance above the floor 12 of the combustion chamber. The tubes 13^a slope slightly upwardly from the header 16^a in the side wall 14 of the combustion chamber to the header 17^a in the front wall 1, while the tubes 13^b slope upwardly from the header 17^a to the header 16^b. Certain of the boiler tubes 3 are broken out so that the pipes 18^a and 19^a may be connected to respective headers 16^a and 16^b. In the construction of Figs. 1 and 2, three of each of such pipes are provided, the outside pipes being connected to the corner boiler tubes which is advantageous in that such tubes are subjected to less temperature and therefore do not carry so much steam. Circulation takes place in the direction of the arrows, as will be readily understood.

The water screen has a double function in that it prevents the products of combustion which may be deposited on the floor of the combustion chamber from turning into a solid mass of slag, difficult of removal, as will further appear, and it also increases the evaporative capacity of the furnace.

Since the surfaces of the tubes comprising the water screen are relatively cool as compared with the temperature of the furnace combustion chamber, the gravitating slag forming refuse as well as that which may be carried along with the flames in proximity to the tubes, will be subjected to the cooling action of the tubes and the deposit, which can be readily removed through the door 15, is largely in the form of small individual lumps or nodules of slag or slag-like matter, the temperature of which, as a result of the absorption of the radiant heat by the tubes, will be maintained below the temperature at which the lumps will melt and run together, and thus fusing or coalescing of the deposit into a mass of liquid slag.

which solidifies into a cake on cooling is prevented. At the same time the chilling effect of the tubes on the flames themselves will have the effect of arresting or partly arresting the flames.

The arrangement of screen is such as to greatly increase the number of tubes and it will be seen that such tubes are subject to the heat from the flames as well as the radiant heat from the floor so that an increase in evaporation is secured. This end is further served by locating the pipes 19^a within the chamber and adjacent the wall 18.

Still greater efficiency is obtained if the number of the pipes 19^a be as illustrated in Figs. 3 and 4, for such arrangement, in addition to increasing the absorption areas, will permit the steam generated in the screen to expand and pass more freely into the boiler. More rapid and adequate circulation through the screen is thus ensured and general efficiency enhanced. Instead of the form of connection shown in Figs. 1 and 2, headers 18^b and 19^b of Figs. 3 and 4 or the arrangement of Fig. 5, may be used.

I prefer to form the side walls of the furnace with the reentrant portions 20 near the bottom so that the slag which forms on the walls thereabove will drip off and be subjected to the cooling action of the water screen.

In the modification shown in Figs. 6 and 7, the headers 16^a and 16^b for the tubes 13^a and 13^b are located in the rear face of the wall 14 and connections to the boiler are arranged as follows:—A pair of headers 21 and 22 are anchored, approximately at the floor line, in the chamber B formed by the bridge walls 14^a and 14^b and the floor 14^c. Pipes 18^c, preferably four in number, bent in the shape indicated in Figs. 6 and 7, connect the headers 21 and 16^a, substantially similar pipes 19^c connecting headers 22 and 16^b. Clover leaf headers 23 and 24 are anchored to the bridge walls 14^a and 14^b respectively, there preferably being four of such headers, in each group, pipes 18^d connecting the headers 23 to header 21 and pipes 19^d connecting the headers 24 to header 22. The shape of these pipes is shown in Fig. 7. Each of the clover leaf headers is connected with a plurality of the corner tubes of the boiler.

The advantages of this arrangement are that expansion is taken care of without undue expansion in any one direction and

working on the ends of the tubes expanded in the clover leaf headers is prevented. As before noted the connections are made to the corner tubes which carry the least steam which frees the screen more freely of its steam and secures more uniform working of the tubes.

It will also be noted that the tubes of the boiler are baffled at 25, 26 and 27 so as to cause the hot gases to flow through chamber B subjecting the pipes located therein to their heat.

No claim is made herein to the particular arrangement of the upright tubes which connect the U-shaped screen into the circulation of the boiler as this is embraced in the subject matter claimed in my copending application, Serial No. 588,564, filed September 16th, 1922.

I claim:

1. In a furnace for burning pulverized fuel, the combination of a boiler, a combustion chamber, a transverse water screen for cooling falling refuse passing out of the flame in regular continuous operation to the place of deposit beyond said screen, said screen comprising two oppositely inclined sets of tubes extending through the combustion chamber with the tubes of one set staggered with respect to the tubes of the other set, a common header for one end of said tubes, a header for each set at the other end, and means for connecting each of said last two headers into the circulation of the boiler.

2. In a furnace for burning pulverized fuel, and the like, the combination of a boiler, a combustion chamber, a transverse water screen for cooling refuse particles precipitating out of the flame to the place of deposit below said screen, said screen comprising two oppositely inclined rows of tubes connected in series, at one end, the tubes of each row being laterally spaced and the rows being vertically spaced, the tubes of one row being staggered with respect to the tubes of the other row and the spacing of the tubes being such that the refuse particles precipitating out of the flame pass freely therebetween to the point of deposit, and means whereby a circulation of water takes place thru said screen.

In testimony whereof, I have hereunto signed my name.

JOHN E. BELL.
